UNITED STATES PATENT OFFICE.

FRANK McLAUGHLIN, OF PHILADELPHIA, PENNSYLVANIA.

WINDOW-SCREEN.

1,074,571.

Specification of Letters Patent. Patented Sept. 30, 1913.

Application filed July 5, 1912. Serial No. 707,807.

To all whom it may concern:

Be it known that I, FRANK McLAUGHLIN, a citizen of the United States, residing in Philadelphia, Pennsylvania, have invented 5 certain Improvements in Window-Screens, of which the following is a specification.

The object of my invention is to so construct a window screen and to so combine the same with the sash in connection with 10 which it operates that said screen will not interfere with the full closing of the sash or with the swinging of the same in the case of a swinging sash, will completely protect the opening formed when the sash is raised, but 15 will only partly screen the sash when the sash is lowered, and will not therefore, under the latter circumstances, obstruct the view through the upper part of the sash pane. This object I attain in the manner 20 hereinafter set forth, reference being had to the accompanying drawing, in which—

Figure 1 is a sectional perspective view of part of a window frame, its sashes, and the screen operating in conjunction with the 25 lower sash, showing the parts in the position assumed by them when said sash is lowered; Fig. 2 is a similar view showing the parts in the position assumed by them when the lower sash is raised, and Fig. 3 is a trans- 30 verse sectional view on a larger scale than Figs. 1 and 2.

In Figs. 1 and 2 of the drawing, 1 represents part of the window frame or casing, 2 the lower sash, and 3 the upper sash, which 35 are guided in the window frame in the usual way. The screen is composed of two sections 4 and 5, with frames adapted to guideways 4^a and 5^a on the opposite sides of the window frame, these guideways being, by preference, 40 formed in bars or strips 6 secured to the opposite sides of the window frame, and the outer screen section 4 being free to slide vertically, independently of the inner section 5. One of the horizontal bars of one of the 45 screen sections is provided with a strip or bar 7 for bearing against the adjoining face of the other screen section so as to prevent insects from entering the room or apartment between the two sections of the screen 50 when the outer section is raised. In the

present instance this stop bar is applied to the upper bar of the inner screen frame but it may, with the same effect, be applied to the lower bar of the outer screen frame, if desired.

The lower member of the sash 2 is provided with lugs or a bar 8, Fig. 3, for engagement with a projecting member 9 on the frame of the outer screen section. When the lower sash is down or only partly raised, 60 the screen sections are also lowered to the position shown in Fig. 1 and occupy a position one behind the other, so that the view through the sash pane above the screen sections is not obstructed or obscured. When 65 the lower sash is fully raised, as shown in Fig. 2, the member 8 of the sash engages with the member 9 of the outer screen frame and raises said outer section of the screen in its guideways so as to completely screen 70 the opening formed by the raising of said lower sash. When the sections of the screen are lowered they do not interfere with the swinging of the sashes in that type of window in which the sashes are pivoted about 75 midway of their length. As the screens are out of the path of the moving sash they will not prevent the lowering of the latter down to the sill, and hence will permit of the locking together of the upper and lower sashes 80 in the usual way.

I claim:

1. The combination of a window frame and sash with a screen composed of a plurality of sections, each less in height than the lift of the sash, means for engaging the outer section with the sash, whereby, as the latter is raised, it will cause the screen sections to be extended, and guides for said screen sections independent of the guides for the sash, whereby the presence of the screens does not prevent the full closing of the sash.

2. The combination of a window frame and sash with a screen comprising a plurality of sections, each less in height than the lift of the sash but capable, when extended, of closing the full opening formed by the lift of the sash, said screen sections being disposed beyond the face of the sash 100

so as not to interfere with the full closing of the latter, and means upon the sash for engaging and lifting the outer section of the screen, said lifting means being free from engagement with the screen section when the latter has been lowered and the sash continues its downward movement.

In testimony whereof, I have signed my name to this specification, in the presence of two subscribing witnesses.

FRANK McLAUGHLIN.
